TRASH RECEPTACLE

Philip M. Baldwin, 2514 Maple Spring Blvd., Dallas, Tex. 75235, and William E. Harlan, 204 N. Rockhill Road, Webster Groves, Mo.

Filed Apr. 22, 1970, Ser. No. 22,552

Term of patent 14 years

Int. Cl. D7—05

U.S. Cl. D49—30

FIG. 1

FIG. 3

FIG. 2

FIG. 4

FIG. 1 is a top plan view of a trash receptacle showing our new design;

FIG. 2 is a bottom plan view;

FIG. 3 is a side elevation view; and

FIG. 4 is a perspective view thereof.

The sides of the trash receptacle not shown are substantially the same in appearance as the sides shown.

We claim:

The ornamental design for a trash receptacle, as shown and described.
